UNITED STATES PATENT OFFICE.

JESSE R. YOUNG, OF LINCOLN, NEBRASKA, ASSIGNOR OF ONE-HALF TO
CHARLES L. ALDRICH, OF SAME PLACE.

TRACE-CARRIER.

SPECIFICATION forming part of Letters Patent No. 328,630, dated October 20, 1885.

Application filed March 5, 1885. Serial No. 157,845. (No model.)

To all whom it may concern:

Be it known that I, JESSE R. YOUNG, a citizen of the United States, and a resident of the city of Lincoln, in the county of Lancaster and State of Nebraska, have invented certain new and useful Improvements in Trace-Carriers; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

15 My invention relates to an improvement in trace-carriers for harness; and it consists in a spring so arranged as to prevent the trace from coming off from the book.

In the accompanying drawings, Figure 1 is 20 a plan view of my improved trace-carrier. Fig. 2 is a longitudinal section of the same made on the line S S, Fig. 1. Fig. 3 is a cross-section made on the line Z Z.

The combined ring or frame-work A A of 25 the carrier is similar to those already in use;

but the part B, which forms the seat for the spring C, is enlarged and made with a mortise or slot to receive the spring. The spring C is made of steel or brass, and extends forward under the two horns H H, upon which 30 the traces are to be carried.

In use the cockeye of the trace is hooked over the horn H, depressing the spring C, which, upon regaining its position, secures the trace upon the horn.

Having thus fully described my invention, what I claim, and desire to secure by Letters Patent, is—

A trace-carrier, consisting of the combined ring or frame A, horns H H, and spring C, 40 when constructed and operated substantially as set forth.

In testimony that I claim the foregoing as my own I affix my signature in presence of two witnesses.

JESSE R. YOUNG.
